UNITED STATES PATENT OFFICE.

WILLIAM H. BLAUVELT, OF SYRACUSE, NEW YORK.

CHARGING OR FEEDING DEVICE.

No. 818,862.

Specification of Letters Patent.

Patented April 24, 1906.

Application filed September 26, 1905. Serial No. 280,145.

To all whom it may concern:

Be it known that I, WILLIAM H. BLAUVELT, a citizen of the United States, residing at Syracuse, in the county of Onondaga and 5 State of New York, have invented a new and useful Charging or Feeding Device, of which the following is a specification.

My invention relates to improvements in charging or feeding devices.

10 My object is to provide improved means for delivering material from a source of supply to a desired point or series of points in required quantity or quantities.

15 My invention also comprises means for delivering material operating over a required range of space or into a receptacle having a considerable longitudinal extension, so that the material will be delivered evenly throughout said extension.

20 My invention comprises means for adjustment whereby the amount of material to be delivered may be varied at will.

25 While my improved means may be adapted to a number of various uses, one special adaptation, which I select for purposes of illustration, is the delivering of finely-ground coal into a box where the same is tamped into a self-sustaining cake.

Referring to the drawings, Figure 1 is an 30 elevation of my device shown in connection with cake-forming mechanism. Fig. 2 is a vertical section on line 2' 2' of Fig. 1. Fig. 3 is a plan view of the deflectors and car for carrying the same. Fig. 4 is an enlarged 35 plan view of the deflector. Fig. 5 is a detail in elevation of the gear mechanism. Fig. 6 is a detail in elevation of the same gear mechanism viewed transversely.

Similar numerals refer to similar parts 40 throughout the several views.

In the concrete example shown in the drawings, 1 represents a bin for a supply of ground coal, having an opening 2 at the bottom of said bin which extends substantially 45 along its entire front. This bin has an inclined wall 3 extending from the rear wall 4 to near the front portion of the bin for insuring the delivery of the material to the deflector 5. The portion of the bin-bottom 6 which 50 is traversed by the deflector 5 is horizontal to conform to the horizontal extension of said deflector. This horizontal portion extends sufficiently beyond the front of the bin to support the material at its angle of rest or 55 natural slope. Beyond the front extension of this bottom 6 is the inclined extension 7

for delivering the coal to the box or receptacle 8.

The deflector 5 is carried by the bracket 9, which is secured to the car 10, mounted on 60 wheels 11, which travel on the tracks 12. This car 10 should preferably have a travel sufficient to carry the deflectors along the entire extension of the opening 2 of the bin—that is, so that each deflector may travel to 65 one end of said opening 2. The car 10 is operated by an electric motor 13, driving the shaft 19 through gears 31 and 32. The shaft 19 is operatively connected alternately with one or the other pairs of wheels 11 through 70 the oppositely-acting skew-gears 14 or 15, respectively, by the clutches 16 and 17. These clutches are controlled by the reciprocating rod 33, operated by the hand-lever 18, so that either gears 14 or 15 may be brought 75 into operative relationship with the motor by shifting the rod 33. The rod 33 is adapted to extend beyond the car 10 at either end to engage with suitably located stops 21, one only being shown in Fig. 1. The movement 80 of rod 33, due to its engagement with either of stops 21, serves to automatically reverse the clutch relationship, and consequently reverse the direction of operation of the car, so that said car will be automatically reciprocated from one end of the track to the other or within any required range of movement 85 on said track.

I have also shown as operated by the same motor the tampers 22. Both being alike in 90 construction and operation, one only need be described. The tamper is mounted on a vertically-reciprocating rod 23, which is properly guided in the framework of the car and is provided with a rack 24 for coöperating 95 with the sector-gear 25, driven by the motor-driven shaft 19 through gears 26 and 27. The grooved wheel 28 is provided as a support or guide for said rod 23 approximate the point of engagement with sector-gear 25. It 100 will be seen that by the rotation of sector-gear 25 in the direction of the arrow shown in Fig. 2 the rod 23 will be elevated during its engagement with said sector-gear, while during the balance of the travel of the sector-gear the rod will be permitted to fall and will 105 then be again engaged, thereby causing the reciprocation of the tamper 22.

The operative engagement between the shaft 19 and gear 26 is secured by the clutch 110 29, operated by the hand-lever 30.

The construction of the deflector 5 is best

shown in Figs. 2 and 4. This deflector preferably comprises two blades 34 and 35, pivoted together by the pin 36, which is secured to bracket 9. Through the apertured extensions 40 and 41 of blades 34 and 35 extend the eyebolts 38 and 39, which are pivotally secured to the pin 37, which is secured to bracket 9. It will thus be seen that the desired angular adjustment of blades 34 and 35 is secured by maintaining the apertured extensions 40 and 41 in the required positions on eyebolts 38 and 39 by the adjusting-nuts 42. It will thus be seen that by the reciprocation of the deflector 5 in either direction along the bin the blade 34 or blade 35, as the case may be, will present a face inclined to its lines of travel, so as to work the material through the opening 2 of bin 1.

Over the deflector-blades 34 and 35 is secured the cover-plate 43 to prevent the material from working in between the two deflector-blades, and thereby becoming jammed. The cover plate or shield 43 is secured to and supported by the bracket 9.

It is also to be noted that a member or curtain 45 is adapted to be elevated or lowered to alter the dimensions of opening 2.

The operation of my device is as follows:

The receptacle 8 is suitably placed to receive the material as it falls from the inclined portion 7 of the bin. The car is so mounted on stationary tracks as to hold the tampers 22 directly over the box, so that said tampers may readily be reciprocated in and out of the same. The tampers are located each at approximately the apex of a sector-shaped deflector formed by the two blades 34 and 35, so that when the car is moved in either direction the inclined face of the deflector sweeping the bottom of the bin 1 discharges the coal into the box directly in front of the tamper, so that as the car is reciprocated backward and forward in front of the bin and over the box the said box is being evenly filled from end to end, the material at the same time being tamped or rammed down almost immediately as it flows into the box.

The discharge of coal into the box may be varied to suit the capacity of the tampers or for any other reason by varying the angular position of the deflectors 34 and 35. A further adjustment of the amount of feed per reciprocation of the deflector is secured by the movement of the curtain 45 to enlarge or diminish the size of opening 2.

What I claim is—

1. The combination of a container, having a longitudinal opening along the lower portion of one side and means connected thereto with for maintaining material at natural slope, a deflector projecting into said opening having its deflecting-face inclined to the line of its travel, and means for moving said deflector.

2. The combination of a bin provided with

a horizontal opening along the lower portion of one side, a deflector projecting into said opening, and means for reciprocating said deflector in directions parallel with the bin.

3. The combination of a bin provided with an opening along the lower portion of one side, a deflector having a deflecting-face at an angle with the lines of its travel, said deflector projecting into the bin through said opening, means for supporting the deflector and means for moving the supporting means in directions parallel with the bin. 75

4. The combination of a bin provided with a horizontal opening extending along the lower portion of one side, a deflector projecting into said opening, having oppositely-disposed deflecting-faces inclined to the lines of its travel, and means for moving said deflector in directions parallel with the bin. 80

5. The combination of a bin provided with a horizontal opening extending along the lower portion of one side, a deflector projecting into said opening, having oppositely-disposed deflecting-faces inclined to the lines of its travel, a cover-plate positioned above said deflector, and means for moving said deflector and cover-plate in directions parallel with the bin. 85

6. The combination of a bin having a horizontal opening along the lower portion of one side, a deflector projecting into said opening having its deflecting-face inclined to the lines of its travel, means for changing the inclination of said deflecting-face, and means for moving said deflector in a direction parallel 90 with the bin. 95

7. The combination of a bin having a horizontal opening along the lower portion of one side, a deflector projecting into said opening having oppositely-disposed deflecting-faces 105 inclined to the lines of its travel, means for changing the inclination of said deflecting-faces, and means for moving said deflector in directions parallel to the bin.

8. The combination of a bin having a horizontal opening along the lower portion of one side, a deflector projecting into said opening having oppositely-disposed deflecting-faces inclined to the lines of its travel, a cover-plate positioned above said deflector, means for 110 changing the inclination of said deflecting-faces, and means for moving said deflector and cover-plate in directions parallel to the bin. 115

9. The combination of a bin having an opening extending along the lower portion of one side, a deflector projecting into said opening having oppositely-disposed deflecting-faces inclined to the lines of its travel, means for supporting said deflector, means for moving 120 the supporting means in opposite directions parallel with the bin, and automatic means for reversing the direction of travel of said supporting means. 125

10. The combination of a bin having a hori- 130

- zontal opening along the lower portion of one side, a deflector projecting into said opening having its deflecting-face inclined to its line of travel, tamping means positioned approximate the point of discharge of the deflector, and means for moving said deflector and tamping means in directions parallel with the bin.
11. The combination of a bin having a horizontal opening along the lower portion of one side, adjustable means for varying the extent of said opening, a deflector projecting into said opening having its deflecting-face inclined to its line of travel, and means for moving the deflector in opposite directions parallel with the bin.
12. The combination of a bin having a horizontal opening along the lower portion of one side, and having a bottom partly inclined and partly horizontal, a deflector projecting into said opening and over said horizontal portion, said deflector having its deflecting-face inclined to its line of travel, and means for moving the deflector in opposite directions parallel with the bin.
13. The combination of a bin having a horizontal opening along the lower portion of one side, a deflector projecting into said opening, having its deflecting-face inclined to its line of travel, a car for supporting said deflector, a motor for operating the car, and means for reversing the direction of movement of the car.
14. The combination of a bin having a horizontal opening along the lower portion of one side, a deflector projecting into said opening having its deflecting-face inclined to its line of travel, means for moving the deflector in opposite directions parallel with the bin, said moving means comprising a wheel-supported car, a motor oppositely-acting gear mechanism connected with different wheels of the car, and clutch mechanism for establishing operative relationship between said motor and each of said gear mechanisms alternately.
15. The combination of a bin having a horizontal opening along the lower portion of one side, a deflector projecting into said opening having its deflecting-face inclined to its line of travel, and means for moving the deflector in opposite directions parallel with the bin, said moving means comprising a wheel-supported car, a motor, oppositely-acting gear mechanism related with different wheels, clutch mechanism for establishing operative relationship between the motor and each of said gear mechanisms alternately, and automatic means for operating the clutch mechanism.
16. The combination of a bin having a horizontal opening along the lower portion of one side, a deflector projecting into said opening having its deflecting-face inclined to its line of travel, means for moving the deflector in opposite directions parallel with the bin, said moving means comprising a wheel-supported car, a motor, oppositely-acting gear mechanisms for different car-wheels, manually-operative clutch mechanism for establishing operative relationship between said motor and said gear mechanisms respectively.
17. The combination of a bin having a horizontal opening along the lower portion of one side, a deflector projecting into said opening having its deflecting-face inclined to its line of travel, a receptacle for receiving the deflected material, tamping means for operating upon the material in the receptacle, the relation between the deflecting means and the tamping means being such that the material is delivered into the receptacle just in advance of the operation thereon by the tamping means, and means for moving said deflector and tamping means in directions parallel with the bin.
